Primary Examiner — Cynthia Underwood(74) *Attorney, Agent, or Firm* — Lewis Roca Rothgerber LLP(57) **CLAIM**

The ornamental design for an electronic device cover, as shown and described.

DESCRIPTION

The present application is related to co-pending U.S. design patent application Ser. No. 29/429,752 filed Aug. 15, 2012. FIG. 1 is a perspective view of an electronic device cover in a standing position showing my new design, an electronic device is also shown in broken lines for environmental purposes only and forms no part of the claimed electronic device cover design;

FIG. 2 is a front view thereof in a flat, open position;
FIG. 3 is a top view thereof in a flat closed position;
FIG. 4 is a front view thereof in a flat closed position;
FIG. 5 is a right side view thereof in a flat closed position;
FIG. 6 is a left side view thereof in a flat closed position;
FIG. 7 is a bottom view thereof in a flat closed position; and,
FIG. 8 is a rear view thereof in a flat closed position.
The short dotted lines represent stitching and form part of the claim.
